JAMES URMSTON AND FREDERICK STRETTON SMITH, OF LONDON, ENGLAND

TELEPHONE REPEATER CIRCUIT ARRANGEMENT

Application filed February 11, 1930, Serial No. 427,592, and in Great Britain February 15, 1929.

Those portions of telephone circuits in which repeating devices are inserted are, as is well-known, only effective for currents flowing in one direction since the amplifying action of the repeater is only applied to currents flowing in one direction. Accordingly, for such telephone lines, two circuits are necessary, which, when considered from one end, may be called the "incoming" and the "outgoing" circuit, respectively. For combined two-way working it is a practical necessity to couple these two circuits together at each end. At this coupling, there is the "incoming" and the "outgoing" circuits and the joint circuit which may, for instance, be the "local" circuit in which the telephone instrument is inserted. By this coupling, it is provided that two-way working from the joint circuit may take place, that is to say, currents originating in the local circuit may flow out and pass into the outgoing circuit, and currents arriving by the incoming circuit may pass to the local circuit. There is, however, unless precautions are taken to prevent it, the possibility that currents arriving by the incoming circuit may pass in part into the outgoing circuit and re-circulate through the line, producing the effect of echoes. The present invention provides an improved arrangement for bringing about this inter-connection of the incoming circuit, the outgoing circuit, and the local circuit, without permitting the re-circulation of an appreciable proportion of the incoming currents.

It will be seen that at the point of inter-connection, the outgoing circuit may have applied to it, currents going from the local circuit or from the incoming circuit; the former must be allowed to pass as freely as possible, while the latter must be restricted as much as possible. One of the methods proposed for attaining this result is the use of an arrangement of a double inductive coupling between the incoming and outgoing circuits so formed that the two parts of the coupling produce effects which oppose each other in the outgoing circuit when they are energized by currents which arrive at the junction by way of the incoming circuit. By application Serial No. 361,624 filed 9th May 1929 an im- proved arrangement of this kind has been described. In that arrangement the two transformers by which the two inductive couplings between the incoming and outgoing circuits are brought about are the junction transformer by which the outgoing and local circuits are coupled with the incoming circuit and a second transformer called the coupling transformer which establishes a second link between the incoming and outgoing circuits. Each of these transformers has a winding in the incoming circuit and a winding which is either placed directly in the outgoing circuit or is otherwise caused to be effective in that circuit. By appropriate design of the transformers and their associated circuits it is provided that when current is arriving at the junction by way of the incoming circuit the effects of the two windings on the outgoing circuit are substantially equal and opposite and therefore produce no appreciable resultant. On the other hand the arrangement provides that the coupling transformer leaves unaffected or assists the effect in the outgoing circuit of currents which arrive at the junction by way of the local circuit. This differentiation between the action of currents on the outgoing circuit in accordance with the path by which they reach the junction is obtained by the difference of phase relation of the currents in the incoming and outgoing circuits in the two cases which results from the form of coupling between the three circuits made by the junction transformer.

The present invention is an improvement in or modification of the subject matter of the above mentioned applications.

In accordance with this invention the second inductive coupling is connected with the incoming circuit at a point in that circuit, where a thermionic valve is interposed between the connection and the junction. One of the results of this arrangement is that currents coming to the junction by way of the local circuit, cannot penetrate to an appreciable extent through the incoming circuit to the coupling circuit.

Since this arrangement will in general provide that amplification of the incoming current takes place between the connection to

the coupling circuit and the junction transformer, it is necessary to provide for a similar amplification in the coupling circuit, so as to obtain the desired equality between the two effects applied to the outgoing circuit by current arriving at the junction through the incoming circuit. A suitable arrangement is obtained by connecting a valve in parallel with the grid and filament connections of the valve in the incoming circuit and connecting the anode and filament of this valve in series with a winding of the coupling transformer, an appropriate battery being also included.

The invention will be further described by the aid of the accompanying drawing which shows diagrammatically the application of the invention to a circuit arrangement as shown by Figure 3 of the drawings of the application previously referred to. From this example the application of the invention to other arrangements, for instance that of Figure 4 of the previous case, will be readily recognized. The incoming circuit 1 is coupled with the outgoing circuit 2 and the local circuit 3 by the transformer having the windings 4, 5 and 6, that is the junction transformer. The other inductive coupling is effected by way of the transformer having the windings 8, 17 and 9. The winding 8 being associated with the incoming circuit, the winding 9 with the outgoing circuit and the winding 17 with an artificial balancing network 18. The windings 9 and 5 are connected in series in the grid filament circuit of the valve 10 and are so connected as to oppose each other when energized by currents coming to the junction by way of the incoming circuit.

In accordance with the present invention the winding 8 is connected with the incoming circuit at a point where the valve 15 is interposed between the connection and the junction and a second valve 20 is arranged as part of the circuit of the winding 8. This valve has its filament and grid connected in parallel with the filament and grid respectively of the valve 15. The winding 8 is in the filament-anode circuit of this valve 20.

With this arrangement currents arriving by way of the incoming circuit will influence equally the grids of both valves 15 and 20 and accordingly will give rise to similar effects in the windings 4 and 8 which will be communicated to the windings 5 and 9 so as to be substantially equal and opposite therein. This arrangement provides for the second inductive coupling without placing any additional load on the valve 15 so that the whole of the output of this valve energizes the junction transformer and passes thereby to the local circuit instead of being divided between this circuit and the balancing network 18 as is the case where the coupling transformer is connected with the incoming circuit at a point between the valve 15 and the junction.

The new arrangement will also modify the conditions which exist when the currents arrive at the junction by way of the local circuit since the one-way connection between the anode filament and grid filament circuits of the amplified valve 20 is now present and makes the effect transmitted through the coupling transformer from the outgoing to the incoming circuit negligible.

The valve 20 should match the valve 15 both as regards its characteristics and the conditions under which it works. Small discrepancies in the inherent characteristics of the two valves may be dealt with by appropriate adjustment of the filament currents or by feeding the grid of one of the valves so that it receives at all times a voltage proportionate to but less than that applied to the grid of the other valve, or the two methods of adjustment may be used in combination. The grid voltage adjustment may be obtained by utilizing a tapped transformer or choke coil or resistance placed across the incoming circuit. This matching of characteristics of valves is required since it is important that the characteristics of the two circuits, by which the incoming and outgoing circuits are connected together, should resemble each other as closely as possible.

The elements of the two valves 15 and 20 may conveniently be combined together in a single structure preferably having a single filament and one or two grids and two anodes, the two arrangements being electrically symmetrical so as to give matched characteristics.

The invention is applicable in the same way as the arrangements described in the earlier applications mentioned to four-wire and two-wire circuits.

What we claim as our invention and desire to secure by Letters Patent is:—

1. A telephone repeater circuit arrangement comprising an incoming circuit, an outgoing circuit, a local circuit, two inductive coupling devices between the incoming and outgoing circuits, opposing each other in their effects in the outgoing circuit when energized by currents which arrive at the junction through the incoming circuit; one of said coupling devices being the junction transformer by which the outgoing and the local circuits are coupled with the incoming circuit and the other of said devices being the coupling transformer, for coupling the incoming and the outgoing circuits; an amplifier arrangement, said amplifier arrangement comprising two similar amplifiers one of which is inserted in the incoming circuit and feeds the junction transformer and the other of which is connected on its input side in parallel with the input of the first amplifier and on its output side is connected with a winding of the coupling transformer.

2. A telephone repeater circuit arrange-

ment comprising an incoming circuit, an outgoing circuit, a local circuit, two inductive coupling devices between the incoming and outgoing circuits, opposing each other in their effects in the outgoing circuit when energized by currents which arrive at the junction through the incoming circuit; one of said coupling devices being the junction transformer by which the outgoing and the 10 local circuits are coupled with the incoming circuit and the other of said devices being the coupling transformer which couples the incoming and the outgoing circuits and comprises a winding connected to a balancing 15 network; and an amplifier arrangement comprising two similar amplifiers one of which is inserted in the incoming circuit and feeds the junction transformer and the other of which is connected on its input side in parallel with the input of the first amplifier and on its output side is connected with a winding of the coupling transformer.

3. A telephone repeater circuit arrangement comprising an incoming circuit, an outgoing circuit, a local circuit, two inductive coupling devices between the incoming and outgoing circuits, opposing each other in their effects in the outgoing circuit when energized by currents which arrive at the junction through the incoming circuit and an amplifier arrangement, one of said coupling devices being the junction transformer comprising a winding in the outgoing circuit, a winding in the incoming circuit and a winding in the local circuit and the other said device being the coupling transformer comprising a winding in the outgoing circuit, a winding connected with the amplifier arrangement and a winding connected with a balancing network; the amplifier arrangement comprising two similar amplifiers one of which is inserted in the incoming circuit and feeds the junction transformer and the other of which is connected on its input side in parallel with the input of the first amplifier and on its output side is connected with the before mentioned winding on the coupling transformer.

In testimony whereof we have hereunto set 50 our hands.

JAMES URMSTON.

FREDERICK STRETTON SMITH.
